TABLET ARM FOR A FOLDING CHAIR

Bror W. Henrikson, Grand Rapids, Mich., assignor to American Seating Company, Grand Rapids, Mich., a corporation of New Jersey

Application August 23, 1954, Serial No. 451,425

5 Claims. (Cl. 155—128)

The present invention relates to folding chairs and more particularly to a folding chair having a tablet arm.

The primary objects of the invention are to provide a tablet arm chair which is foldable into a compact unit for storage when not in use; to provide such a tablet arm folding chair from which the tablet arm and its supporting element may be removed when it is desired to use the chair without the tablet arm; to provide such a tablet arm chair in which the tablet arm overhangs the chair seat for convenience in use, said tablet arm also being swingable upwardly to one side of the chair to permit easy access to and from the chair seat in instances where such chairs are placed closely together in rows; and in general to provide such a folding tablet arm chair which is simple but sturdy in construction, reasonably economical in manufacture and attractive in appearance.

An illustrative embodiment of the invention is shown in the accompanying drawings, wherein:

Figure 1 is a side elevational view of the new tablet arm folding chair in its unfolded position of use;

Figure 2 is a side elevational view of the chair in its folded position for storage;

Figure 3 is a rear and side perspective view of the chair in unfolded position with the tablet arm thereof in position for use;

Figure 4 is a front and side perspective view of the chair in unfolded position with the tablet arm thereof swung upwardly;

Figure 5 is a front and side perspective view of the chair in folded position for storage;

Figure 6 is an enlarged fragmentary side elevational view of parts of the chair showing a connection between the tablet arm support and a front leg of the chair; and

Figure 7 is a sectional view of the same taken on line 7—7 of Figure 6.

Referring now in detail to these drawings the chair there shown has an inverted U-shaped tubular metal front frame 10 providing spaced front legs 11, 12 connected at their upper ends by a bight 13 which serves as a support for a back rest 14. A chair seat 15 is provided with seat arms 16, 17 secured to its underside on opposite sides of the seat, and these seat arms 16, 17 are pivotally connected at points 18, 19 intermediate the front and rear of the seat to the front legs 11, 12 of the chair. The rear legs 20, 21 for the chair are also of tubular metal and are pivotally connected to the front legs 11, 12 above the seat 15 by means of metal straps 22, 23 secured to the front legs, to which straps the rear legs are pivotally connected at 24, 25. Links 26, 27 are pivotally connected at 28, 29 to the rear legs 20, 21 below the seat and are pivotally connected at 30, 31 to the seat's arms 16, 17. The rear legs 20, 21 are connected by a lower strut 32 and an upper strut 33, said upper strut 33 additionally serving as a stop against which abut the rear ends of the seat's arms 16, 17 to limit the unfolding movement of the chair. The lower portions of the front legs are also desirably connected by means of a strut 34.

A tablet arm support 35 is secured to one of the front

2

legs of the chair, preferably the right front leg 11. This support 35 is desirably made of metal rod or tubing and is bent to V-shaped form to provide a lower arm 36 pivoted to the front chair leg 11 below the seat level and an upper arm 37 pivoted to the front chair leg 11 above the seat level, so that when the chair is in folded position, the tablet arm support is swingable inwardly to a position paralleling the front frame 10 as seen in Figures 2 and 5. When the support 35 is swung outwardly as seen in Figures 1, 3 and 4, the upper arm 37 thereof extends forwardly from the front chair leg 11 above the seat level.

The tablet arm 38 is pivotally mounted on the upper arm 37 of the tablet arm support by means of spaced bearing straps 39, 40 secured to the underside of the tablet arm and extending around the upper support arm 37. The tablet arm is thus swingable, when the chair is in open or unfolded position, to a lowered position for use as seen in Figures 1 and 3 in which position the tablet arm rests on a substantially horizontal extension 37a secured as by welding to the upper support arm 37, or to a raised position as seen in Figure 4 in which latter position of the tablet arm ready ingress to and egress from the chair seat is provided.

It will be seen that when the tablet arm 38 is in its upwardly swung position seen in Figure 4, the chair can readily be folded by lifting the chair seat 15 thus drawing the rear legs 20, 21 together with the front legs 11, 12, whereupon the tablet arm 38 and its support 35 may together be swung inwardly to folded position adjacent and parallel to the front frame 10, as seen in Figures 2 and 5. When it is desired to again unfold the chair for use, the tablet arm 38 and its support 35 are swung outwardly so as to again occupy their positions seen in Figure 4, whereupon the seat may be lowered thus spreading the front and rear legs to their use positions as also seen in Figure 4. There is desirably provided a latch member 41 secured to the lower arm 36 of the tablet arm support as by means of welding and provided with a slot 42 in which engages the side flange 43 of the chair seat to insure stability to the structure when the chair is in use.

Provision is made for detaching the tablet arm and its support from the chair in instances when it is desired to use the chair without a tablet arm. As best illustrated in Figures 5 and 6, each of the connections between the support's arms 36 and 37 and the front chair leg 11 comprises a pair of clamping members 44, 45 which abut at their forward ends and which engage opposite sides of the front leg 11 at their rearward ends to clamp the leg 11 therebetween. A bolt 46 and nut 47 are provided as shown for drawing the clamping members together to securely grip the front leg 11. Clamping member 44 has inwardly extending upper and lower flanges 48, 49 and clamping member 45 has similar inwardly extending upper and lower flanges 50, 51, said flanges 48, 49, 50 and 51 being provided with registering apertures through which pass the pivot pin 52 by means of which the adjacent lower or upper support arm 36 or 37 is pivotally secured to the front leg 11. It will be seen that the tablet arm 38 and its support 35, together with the upper and lower clamping devices, may readily be detached from the chair by loosening the nuts 47 on bolts 46 thus releasing the clamps from the front chair leg 11.

It will thus be seen that the invention provides a novel and sturdy folding tablet arm chair which is effective in use and which can be folded compactly for storage, and while but one specific embodiment of the chair has been herein shown and described it will be understood that numerous details thereof may be altered or omitted without departing from the spirit of the invention as the same is defined by the following claims.

I claim:

1. A tablet arm device for a folding chair having a

front frame providing spaced front legs for the chair, a chair seat pivotally mounted on and between said front legs, and rear legs for the chair pivotally connected to the front legs, said device comprising: a tablet arm support pivotally connected to one of said front legs for swinging movement inwardly to a position paralleling the front frame and outwardly to a position wherein its upper portion extends forwardly from said front leg above the seat level, and a tablet arm pivotally mounted on said upper portion of the tablet arm support.

2. A tablet arm device for a folding chair having a front frame providing spaced front legs for the chair, a chair seat pivotally mounted on and between said front legs, and rear legs for the chair pivotally connected to the front legs, said device comprising: a tablet arm support pivotally connected to one of said front legs for swinging movements inwardly to a position paralleling the front frame and outwardly to a position wherein its upper portion extends forwardly from said front leg above the seat level, and a tablet arm pivotally mounted on said upper portion of the tablet arm support for swinging movements, when the chair is unfolded, about a forwardly-rearwardly extending axis to a lowered position of use extending forwardly and above the chair seat and to a raised position at one side of the chair, in which latter position the tablet arm is swingable, when the chair is folded, inwardly and outwardly with the tablet arm support.

3. A tablet arm device for a folding chair having a front frame providing spaced front legs for the chair, a chair seat pivotally mounted on and between said front legs, and rear legs for the chair pivotally connected to the front legs, said device comprising: a tablet arm support comprising a V-shaped member having one arm thereof pivoted to a front leg of the chair below the seat level and the other arm thereof pivoted to said front chair leg above the seat level whereby the tablet arm support is swingable inwardly to a position paralleling the front frame and outwardly to a position in which the support's upper arm extends forwardly from said front leg above the seat level, and a tablet arm pivotally mounted on said upper arm of the tablet arm support. 40

4. A tablet arm device for a folding chair having a front frame providing spaced front legs for the chair, a chair seat pivotally mounted on and between said front legs, and rear legs for the chair pivotally connected to the front legs, said device comprising: a tablet arm support comprising a V-shaped member having one arm thereof pivoted to a front leg of the chair below the seat level and the other arm thereof pivoted to said front chair leg above the seat level whereby the tablet arm support is swingable inwardly to a position paralleling the front frame and outwardly to a position in which the support's upper arm extends forwardly from said front leg above the seat level, and a tablet arm pivotally mounted on the upper arm of the tablet arm support for swinging movements, when the chair is unfolded, about said upper arm to a lowered position of use extending forwardly and above the chair seat and to a raised position at one side of the chair, in which latter position the tablet arm is swingable, when the chair is folded, inwardly and outwardly with the tablet arm support.
5. A tablet arm device for a folding chair having a front frame providing spaced front legs for the chair, a chair seat pivotally mounted on and between said front legs, and rear legs for the chair pivotally connected to the front legs, said device comprising: a tablet arm support detachably pivotally connected to one of said front legs for swinging movements inwardly to a position paralleling the front frame and outwardly to a position wherein its upper portion extends forwardly from said front legs above the seat level, and a tablet arm pivotally mounted on said upper portion of the tablet arm support.
